Patented Feb. 7, 1922.

FIG. 2.

FIG. 4.

FIG. 6.

INVENTOR

DONALD J. CAMPBELL

BY Frank E. Liverance Jr.
ATTORNEY.

UNITED STATES PATENT OFFICE.

DONALD J. CAMPBELL, OF MUSKEGON HEIGHTS, MICHIGAN, ASSIGNOR OF ONE-FOURTH
TO ROBERT B. CAMPBELL, OF SOUTH HAVEN, MICHIGAN.

SAND-HOPPER CONSTRUCTION.

1,405,398.

Specification of Letters Patent. Patented Feb. 7, 1922.

Application filed March 21, 1921. Serial No. 454,194.

To all whom it may concern:

Be it known that I, DONALD J. CAMPBELL, a citizen of the United States of America, residing at Muskegon Heights, in the county 5 of Muskegon and State of Michigan, have invented certain new and useful Improvements in Sand-Hopper Construction; and I do hereby declare the following to be a full, clear, and exact description of the invention, 10 such as will enable others skilled in the art to which it appertains to make and use the same.

This invention relates to sand hoppers, and is particularly concerned with improvements in hoppers such as may be used with 15 pneumatic sand handling machines, one construction of which is shown in my application for Patent Ser. No. 443,739, filed Feb. 10, 1921. Such machines make use of the 20 force of compressed air for forcing sand into moulds or core boxes to ram and compress the same to the necessary degree of density and with my invention, the force of the compressed air is conserved and practically 25 none of it is lost or dissipated by expansion of the air laterally through an inert body of sand such as would be the case if the hopper was a hollow shell with spaced apart outlet openings at the bottom.

30 In running large jobs, the hopper will be made of metal and the sand passages therethrough are defined by metal sides. Many times, however, it is necessary to run a relatively small job, numbering only a relatively 35 small number of moulds or cores in which case it is not economical or advisable to go to the expense or to spend the time required to make a special metal sand hopper therefor. Accordingly, the present invention has 40 for its primary consideration the construction of a hopper in which a hollow metal shell may be used and equipped with an interior core or filling of easily worked material in which the sand passages may be easily 45 formed, this filler being placed within the outer shell and used for the running of the particular relatively small job ordered, after which the filler may be removed and a different one placed in the shell for another 50 job of different character, the fillers being quickly and easily made and used, and being put in and taken out of the outer shell very quickly, and either discarded after the particular job is done, or kept for future

use should the same job thereafter need to 55 be done again.

For an understanding of the invention and the constructions embodying the same, reference may be had to the following description, taken in connection with the accompanying drawing, in which,

Fig. 1 is a vertical section taken through a hopper made in accordance with my invention.

Fig. 2 is a horizontal section taken substantially on the plane of line 2-2, of Fig. 1.

Fig. 3 is a sectional view similar to that shown in Fig. 1, but in which a larger number of sand passages are made through the 70 filler.

Fig. 4 is a view taken on the plane of line 4-4 of Fig. 3 and looking upwardly as indicated by the arrows.

Fig. 5 is a vertical sectional view through 75 a still further form of hopper, and

Fig. 6 is a view taken on the plane of line 6-6 of Fig. 5, looking upwardly as indicated by the arrows.

Like reference characters refer to like 80 parts in the different figures of the drawing.

The outer shell 1 is of metal open at its top and bottom and formed with an outwardly extending flange 2 at its lower end to which the lower outlet plate 3 may be attached by screws 3^a, as shown. This plate has a plurality of outlet openings 4 made therethrough and when compressed air is applied to sand in the hopper at the upper portion thereof, the sand is forced from the 90 hopper through such openings and into any convenient mould or core box.

With the present invention, a filler 5 is placed within the shell, being shaped at its outer sides to fit against the inner sides of 95 the shell, and being held in place by the attachment of the plate 3. This filler may be of any suitable easily worked material, such as plaster of Paris, wood, or any other material of similar nature which may be either 100 quickly worked or moulded to the desired shape and which has considerable stability as to texture. In this filler, a plurality of passages 6 are made from the lower end to the upper end inclining inwardly toward 105 each other at their upper ends, and having their lower ends positioned directly over the openings 4 in the plate 3. The material be-

tween the inner adjacent sides of the passages 6 is cut away partly so as to make a pointed portion 7, whereby sand entered into the upper portion of the hopper, to which 5 portion the filler does not reach, must all go into the passages and none will lodge on the central portion of the filler between the passages as would be the case if such pointed portion 7 was not made.

10 The sand goes into the hopper at its upper end in the space indicated at 8 from which it passes into the passages 6. Under the force of compressed air introduced into the upper end of the hopper, the sand is 15 forced downwardly in the passages at 6 and out through the openings 4 to the mould. The means for doing this is no concern of the present invention, which is directed to the ready and easy forming of a filler for a 20 hopper shell in accordance with the number of outlet openings through the lower plate, one passage being made for each of the outlets. In Figs. 3 and 4, the same shell 1 and lower plate 3 is shown, except that 25 the plate has a larger number of outlets, this necessitating a correspondingly larger number of said passages 6^a in the filler 5^a which has the same outer form as filler 5. This 30 illustrates the salient feature of the invention, that is, the easy production of different temporary fillers for the same outer hopper shell.

In Figs. 5 and 6, a slight modification is shown, in which the shell 1^a is elongated, 35 having a corresponding plate 3 attached thereto at its under side and the filler 5^b has passages 6^b therein leading downwardly to the outlet openings through the plate. These openings are in alinement and the passages 40 6^b are located one after the other in the length of the filler. This hopper accordingly has four consecutive outlet openings at the bottom and is of value in making certain types of elongated moulds, as 45 for internal combustion engine blocks having four cylinders; and another filler with six sand passages therein and a lower plate 3 with six outlets therein can be very readily placed therein for a different type of mould, 50 as for six cylinder engine blocks, or for the production of six smaller moulds of any type that could be produced four at a time with the filler shown in Fig. 5. In any case, whatever the type of filler used in the shell, 55 it is apparent that the filler is quickly made, and it is also obvious that the shell itself is a simple construction which can be quickly made for the type of work desired, both the shell and filler when both must be made for 60 a particular job, being produced much cheaper than would be the case if the combined shell and filler were made as an integral casting.

I have shown several forms of filler and 65 different shells that may be used, though

not anything like all of the forms which can be utilized in carrying out the invention. The filler made of easily worked or moulded material can be made in a very short time, and if necessary, the outer shell can be made 70 in a very little longer time, while the expense for each is small. This is very important where the lot of moulds to be run is not large enough to warrant the initial expense of making a complete metal filler 75 integral with the shell of the hopper. The filler when it has served its purpose can be detached from the shell and a new filler substituted therefor, if adapted thereto, or a complete shell and inner filler made at 80 little expense or loss of time.

The invention is defined in the appended claims and I consider myself entitled to all forms of structure coming within their scope.

I claim:

1. In combination, a hopper shell, and a 85 filler located therein and detachably connected therewith, said filler having a plurality of sand passages therethrough, substantially as described.

2. In combination, a hopper shell open at its upper and lower ends, a plate having an outlet opening therein closing the lower end of the hopper, and a filler detachably held in the shell by said plate and having a sand 95 passage therethrough extending upwardly from the outlet opening to the upper end of the filler, substantially as described.

3. In combination, a hopper shell open at its upper and lower ends, a plate having a 100 plurality of outlet openings therein closing the lower end of the shell, and a filler detachably held in the shell by said plate and having a plurality of sand passages therethrough extending upwardly, one from each 105 outlet opening in the plate to the upper end of the filler, substantially as described.

4. In combination, a hopper shell, a filler 110 detachably secured within the shell and having a plurality of sand passages therethrough extending from the upper end of the filler downwardly therethrough, said shell having openings at the lower ends of said passages for the outward passage of sand forced into and through said passages, 115 substantially as described.

5. In combination, a hopper shell, and a 120 filler therefor of easily worked material having sand passages therethrough, said filler being adapted to be detachably secured within the shell for removal and replacement by other fillers, substantially as described.

6. In combination, a hopper shell having an upwardly tapered upper portion, a plate 125 having outlet openings therethrough closing the lower end of the shell, means for detachably connecting the plate to the shell, and a filler located in the shell and held therein by the plate, said filler having sand 130

passages therethrough leading from directly over the outlet openings in the plate to the upper end of the filler and converging toward each other at their upper ends, substantially as described.

7. In combination, a hopper shell, a plate having outlet openings therein closing the lower end of the shell, means for detachably connecting the plate to the shell, a filler located in the shell and held therein by said plate, said filler terminating short of the upper end of the shell and having a plurality of sand passages therethrough extending

from the lower to the upper end of the filler, the lower end of each passage being positioned directly over an outlet opening through said plate, substantially as described. 15

8. In combination, a hopper shell, and a filler detachably and replaceably held in said hopper and having a plurality of sand passages therethrough leading downwardly from the upper end of the filler, substantially as described. 20

In testimony whereof I affix my signature. 25
DONALD J. CAMPBELL.
